UNITED STATES PATENT OFFICE.

MARSHAL G. KEEN AND PETER P. KEEN, OF KEENSBURG, ILLINOIS.

GRAIN-REEL FOR REAPING-MACHINES.

SPECIFICATION forming part of Letters Patent No. 606,346, dated June 28, 1898.

Application filed May 4, 1897. Serial No. 634,999. (No model.)

To all whom it may concern:

Be it known that we, MARSHAL G. KEEN and PETER P. KEEN, of Keensburg, in the county of Wabash and State of Illinois, have invented 5 a new and Improved Grain-Reel for Reaping-Machines, of which the following is a full, clear, and exact description.

This invention relates to reels for reaping-machines; and the object is to provide a reel 10 that will take up a small space as compared with the ordinary reels that describe a complete circle in their movements, and, further, to provide a simple means whereby the reel may be adjusted relatively to the cutters, and, 15 further, to so construct the reel that it may be folded down closely upon the platform, making it much more convenient for transportation or storage.

We will describe a reel for reaping-machines embodying our invention, and then point out the novel features in the appended claims.

Reference is to be had to the accompanying drawings, forming a part of this specification, 20 in which similar characters of reference indicate corresponding parts in all the views.

Figure 1 is a front elevation of a reel embodying our invention. Fig. 2 is an end elevation thereof, and Fig. 3 is a sectional view 25 of the means for supporting the reel.

Referring to the drawings, 1 designates the platform of the usual construction and upon the forward edge of which the cutter-blades are mounted. This platform is extended from 30 the frame portion 2 of the reaper. Mounted to swing on the frame 2 is a link 3, and mounted to swing on this link 3 is a reel-supporting link 4. These two links 3 and 4 form, in effect, toggle-links for supporting and adjusting the reel. These two links for the purpose of strength are made substantially in the form of rectangular frames, and they have trunnion connections one with the other.

Attached to the upper end of the link 4 and 45 extending lengthwise of the platform 1 is a tubular shaft 5, within which a reel-operating shaft 6 is designed to rotate. The inner end of the shaft 6 is provided with a sprocket-wheel 7, over which a driving-chain is designed to 50 extend. A tubular shaft 8 also surrounds the shaft 6 between the sprocket-wheels 9 and 10, secured to the shaft 6, and the sprocket-wheel

9 will of course be between the adjacent ends of the tubular shafts 5 and 8. Supported by the tubular shafts 5 and 8 are guideways for 55 the sprocket-chains 11 and 12, the inner guideway being connected to the tubular shafts 5 and 8 by hangers *a b*. The outer guideway is connected to the tubular shaft 8 by a hanger *a'* and is also supported from the shaft 6 by 60 a hanger *b'*. These guideways each comprise diverging side portions 13 and 14 and a bottom portion 15, formed in the arc of a circle. These guideways will be channeled on their outer sides to receive the chains, and preferably we employ rollers 16 at the junction of the side and bottom portions, over which the chains will run, and thus the friction will be materially reduced. A series of reel-boards 65 17 is attached to the chains 11 and 12. These 70 reel-boards of course extend outward from the chains and longitudinally of the platform 1. They may be secured to the chains in any desired manner.

Pivottally connected to the frame 2 is a lever 18, having a link connection 19 with a collar 20 on the tubular shaft 5 above the link 4. The lever 18 has a dog movable relatively to it and designed to engage with an arc-shaped rack 21 to hold the parts adjusted, as 75 is usual in such cases. Also pivotally connected to the frame 2 is another shifting lever 22, having a link connection 23 with the lower link 3 of the toggles. This lever will also be provided with means, as a thumb-latch, engaging a rack 21 for holding it as 80 adjusted. It will be seen by operating the levers 18 and 22 that the reel may be swung forward or rearward relatively to the knives, as may be desired, and also that the reel may 85 be elevated or lowered relatively to the reaper-platform, as occasion may require.

In operation the motion imparted to the shaft 6 will rotate the sprocket-wheels 9 and 10, and consequently the sprocket-chains will 90 be moved around the guides, carrying the reel-boards in the segment of a circle instead of in a complete circle, as heretofore.

As this reel is but little more than half as high as the old-style reel, it will enable the 100 machine to which it is applied to be handled with much greater ease and security from breakage in the vicinity of brush or other obstructions, and in case of transportation of

the machine on trucks it is obvious that the reel may be turned in over the platform out of the way. The two levers make it possible to adjust the reel in any desired position, so 5 that lodged grain may be recovered much more easily than in machines where the old form of reel is employed. The shape of the guideways will enable the reel-boards to have a direct upward stroke on the rear side, which 10 when the reel is properly adjusted in front of a knife will serve to lift the lodged grain from the cutter-bar onto the platform, so that it may be conveyed to the binder.

Another advantage of this form of reel over 15 the old style is that by shifting the inner sprocket-chain on its sprocket-wheel the boards may be adjusted to run diagonally, with the inner ends somewhat forward of the outer ends, thus causing the grain to fall 20 straight onto the platform.

Having thus described our invention, we claim as new and desire to secure by Letters Patent—

1. In a reaping-machine, toggle-links mounted 25 to swing on the frame thereof, means for swinging said links, relatively to the platform and one relatively to the other, a tubular shaft carried by the upper link, a reel-shaft extended through said tubular shaft, 30 means for rotating said reel-shaft, sprocket-wheels on said shaft, sprocket-chains engaging said wheels, guideways for said sprocket-

chains, comprising downwardly-diverging side portions, and a bottom portion suspended in the arc of a circle, and reel-boards attached 35 to the chains, substantially as specified.

2. In a reaper, a link pivotally connected to the frame thereof, another link pivoted to the first-named link, levers having link connections with said links, means for holding 40 the levers as adjusted, a tubular shaft supported by the upper link, a reel-shaft extended through the tubular shaft, means for rotating the reel-shaft, sprocket-wheels on the reel-shaft, another tubular shaft on the reel-shaft 45 between said sprocket-wheels, guideways supported by the tubular shafts and each comprising downwardly-diverging side portions and bottom portions formed in the arc of a circle, rollers at the junction of the side and 50 bottom portions, chains movable in the guideway and engaging with the sprocket-wheels, and reel-boards attached to said sprocket-chains, substantially as specified.

3. In a reaping-machine, a reel, and means 55 for causing said reel to travel in the arc of a circle at its lower portion and in an inwardly-inclined direction at the front and rear, substantially as specified.

MARSHAL G. KEEN.
PETER P. KEEN.
